UNITED STATES PATENT OFFICE.

CHARLES T. KAMMEYER, OF NIAGARA FALLS, NEW YORK.

GALLEY BAR AND PROOF.

Application filed January 20, 1921. Serial No. 438,771.

To all whom it may concern:

Be it known that I, CHARLES T. KAMMEYER, a citizen of the United States, residing at Niagara Falls, in the county of 5 Niagara and State of New York, have invented certain new and useful Improvements in Galley Bars and Proofs, of which the following is a specification.

This invention relates to improvements in 10 printers' appliances and has for its object to provide a galley proof bar so constructed that any portion of the matter on a galley proof may be instantly located upon its galley or rack.

15 Another object of the invention is to provide a galley bar to be used in connection with making galley proofs said bar having signs throughout its length for indicating any portion of the matter in the galley or rack.

Another object of the invention is to provide a galley bar having series of signs throughout its length, numbers of the bar arranged throughout its length and indicia 25 throughout its length to designate for what particular job the matter on the galley is to be used with.

With the above and such other objects in view as may hereinafter more fully appear, 30 I have invented the device illustrated in the accompanying drawings, in which,

Figure 1 is a plan view of my galley bar used in connection with a galley proof,

Figure 2 is a plan view of several similar 35 bars shown broken away, and,

Figure 3 is a plan view of proof dummiied up for the make-up.

Like reference characters indicate like 40 parts throughout the following specification and in the several views in the drawings in which 1 indicates a proof of my galley bar used in connection with a proof of galley matter 2, said bar is formed of a single strip of metal longitudinally divided into three 45 columns 3, 4 and 5, the first column having inserted throughout its length thereon the word "Courier", or any other suitable word to indicate any newspaper, periodical or publication to which the particular piece of 50 matter 2 belongs. Column 4 has printed throughout its length in relatively large type, said type as shown in this particular instance being arranged in series of letters of the alphabet arranged alphabetically 55 from the top to the bottom of the bar and each series of letters being graduated from

the largest letter 7 to the smallest letter 8 in size. The third column 5 is provided with the number of the particular bar, said number being duplicated throughout the 60 length of said column. It is to be understood that as many of these bars as may be necessary for a printing office of any particular size may be used, each bar having a separate number and preferably arranged numerically from one up, Figure 2 showing bars Number 1, 6 and 100. 65

The dummy shown in Figure 3 clearly indicates how matter may be taken from any particular numbered galley and used for 70 making up the dummy and how said dummy will indicate instantly to the imposer just where to locate instantly the matter of the dummy.

A rack having numbered galley portions 75 conforming to the corresponding numbers of the galley bars is preferably used in connection with these bars so as to simplify the location of any matter desired.

With this device any printing plant can be thoroughly systematized in this particular branch using this galley bar in connection with galleys already on hand. The prevailing custom is to mark the galley 80 number on each corresponding form of galley proof. This not only requires considerable time but often errors arise from careless or obscure marking and although clearly and correctly marked and the galley 85 found, time is required to locate the matter on the galley to correspond with the corresponding proof. For lack of time, the name of the particular publication is omitted in marking the clipping which further complicates matters and which is a very important feature and absolutely necessary in large plants where a number of different publications are issued within a given period. My galley bar as above described will 90 obviate the marking of the clippings and indicate instantly not only the publication to which the matter belongs but also its location on the rack and in the galley. 95

Example: One of my galley bars is placed against one side of each galley of matter to be proofed consequently each galley proof includes the imprint of the galley bar as indicated in Figure 1. In making up a dummy it often occurs that clippings a, b, c, d, etc., (see Figure 2) are taken from 100 as many different galley proofs and are used (pasted together) to indicate how a col- 105 110

umn, a page, or form of matter is to be imposed or made up. In referring to the dummy of Fig. 3, the imposer will see at a glance that the matter belongs to the "Courier" (see 6, column 3), he will also see that clipping *a*, is from galley 100; clipping *b*, from galley 1; clipping *c*, galley 1; and clipping *d*, galley 6, etc. (see third column 5) making it very easy to locate the type 10 in the different galleys. Thus, the maker of the dummy, is saved the time usually required for marking the clippings, and the imposer is saved the time usually spent in locating the matter of the clippings. In 15 correcting proof, the compositor can instantly locate any desired line by referring to the alphabetical column 4, of graduated letters.

Having now described my invention, that 20 which I claim to be new and desire to procure by Letters Patent is:

1. A galley bar having a series of printing characters thereon.
2. A galley bar having a series of type high printing characters throughout its length.
3. A galley bar having printing characters thereon for indicating in a galley proof the particular location in said galley of certain lines therein.
4. A galley bar having a series of printing characters thereon, throughout its length, said signs being arranged in columns, one column indicating a particular publication, throughout its length.
5. A galley bar having a series of printing characters thereon, throughout its length said signs being arranged in columns, one column indicating a particular publication, throughout its length, another column indicating the bar number.
6. A galley bar having a series of printing characters thereon, throughout its length said signs being arranged in columns, one column indicating a particular publication, throughout its length, another column indicating the bar number, throughout its length.
7. A galley bar having a series of printing characters thereon, throughout its length said signs being arranged in columns, one column indicating a particular publication,

throughout its length, another column indicating the bar number, throughout its length, another column having indicia to indicate any particular part of a galley in connection with which the bar is used. 55

8. A galley bar having letter forming characters alphabetically arranged throughout its length. 60

9. A galley bar having letter forming characters alphabetically arranged throughout its length, each of said letters being in series.

10. A galley bar having letter forming 65 characters alphabetically arranged throughout its length, each of said letters being in series, each series being graduated.

11. A galley bar having letter forming characters alphabetically arranged throughout its length, each of said letters being in series, each series being graduated, means 70 throughout the length of said bar to indicate the particular job.

12. A galley bar having letter forming 75 characters alphabetically arranged throughout its length; each of said letters being in series, each series being graduated, means throughout the length of said bar to indicate the particular job, said bar being numbered 80 throughout its length.

13. A galley bar having a series of printing characters thereon, said characters reading longitudinally of said bar.

14. A galley bar having a series of printing characters thereon, said characters reading longitudinally of said bar, said characters being type high. 85

15. In a device for the purpose indicated, a bar-like member adapted to extend longitudinally of the type galley or at right angles to the lines of type therein, said bar-like member carrying a column of raised or reproductive index characters adapted to print a corresponding column of characters 95 alongside the printed lines of the proof sheet simultaneously with the printing of such lines from the set-up type.

In testimony whereof I affix my signature in the presence of two witnesses.

CHARLES T. KAMMEYER.
